UNITED STATES PATENT OFFICE.

WILLIAM H. WALTER, OF DENVER, COLORADO.

BROODER STOVE.

Application filed February 3, 1922. Serial No. 533,740.

To all whom it may concern:

Be it known that I, WILLIAM H. WALTER, a citizen of the United States, residing in the city and county of Denver and State of Colorado, have invented certain new and useful Improvements in Brooder Stoves; and I do declare the following to be a full, clear, and exact description of the invention, such as will enable others skilled in the art 10 to which it appertains to make and use the same, reference being had to the accompanying drawings, and to the characters of reference marked thereon, which form a part of this specification.

15 This invention relates to new and useful improvements in stoves, and especially to a stove known as a brooder stove.

It is the object of this invention to provide a stove that shall be of substantial and 20 inexpensive construction, which is built on the hot blast principle and which is provided with a reliable draft regulating attachment which is automatically controlled by a temperature responsive device which 25 serves to keep the temperature from varying too much from that desired.

In order to more clearly describe my invention, I shall have reference to the accompanying drawing, in which

30 Fig. 1 shows a vertical section through my brooder stove, and shows the hood in place thereon;

Fig. 2 is a section taken on line 2—2, Fig. 1;

35 Fig. 3 is a top plan view of the stove, and shows the relative location of the draft feed and flue openings and

40 Fig. 4 is a section on line 4—4, showing the manner of attaching the cover to the stove.

The same reference numerals will be used to indicate the same or similar parts throughout the several views.

Numeral 1 represents the base portion of 45 the stove and 2 represents the fire pot section which is above the grate, while 3 indicates the combustion chamber section of the stove body. It will be noted that the base portion 1 is upwardly tapering, and the fire pot 50 section 2 is downwardly tapering, and at the juncture of the two, I provide a grate 4 beneath which is located an ash pan 5. The combustion chamber section 3 is bolted to the lower part 2 by means of bolts 6 which 55 pass through outwardly extending lugs 7. Extending from a point 10 a short distance

above the upper surface of grate 4 is an air shaft which is formed between the inner side of member 2 and the arcuate part 12. Along the inner surface of member 3 and located 60 directly above shaft 11 is another air passage 13, formed by the inner side of member 3 and the arcuate member 14. Shaft 13 is somewhat larger in cross section than shaft 11, and by this means passage 15 is provided between the two. At the top of member 3, I provide two spaced lugs 16, between which I pivotally mount a damper 17 which is adapted to close the upper end of air passage 13. Damper 17 has an outwardly 65 extending portion 18, to which is pivotally connected a rod 19 whose lower end is connected to lever 20, which is controlled by a thermostatic member 21, supported on a bracket 22 which is secured to the lower 70 inner surface of hood 9 by means of bolts 23. The outer end of lever 20 is movably secured to bracket 22 by means of a bolt 24 and rests upon the projecting portion 25 of the thermostat 21. 75

When the thermostat 21 becomes heated, it expands and moves the end of lever 20 upwardly, whereby the damper 17 is permitted to close and cut off the air supply to the fire, and when the temperature falls 80 the thermostatic member 21 contracts, permitting the lever 20 to move downwardly and open the damper.

The stove is provided with a cover 26 which has a flue opening 27 and a feed opening 28, the latter being closed by a removable cover member 29 having a handle 30. In Fig. 3 I have shown a plan view of the top of the stove and this shows that the draft passage 13, feed opening 28 and flue 85 opening 27 are spaced apart on a diameter, with the feed opening 28 located between the other two; this forms a convenient arrangement and permits the coal to be fed centrally of the stove and makes it necessary 90 for the air to pass from one side of the stove to the other in order to reach the flue 27. By my arrangement, air entering through the passage 13 will partly enter the space above the fire through opening 15, and a 95 portion of it will pass down and enter above the grate 4, while the remainder will pass down below the grate; a good distribution of air is thus obtained. As my air enters from above, it will become highly heated 100 before it enters the combustion chamber and thus permit a greater efficiency to be ob-

tained. A cut-out portion 31 is provided in the hood and enables the same to be removed without removing the damper 17.

On the inside of member 3 near the top 5 thereof, I provide lugs 8 to which the top 26 is secured by top bolts 31. The hood 9 is provided with legs 32 by means of which it is supported on the floor 33. Legs 32 are preferably made of U-shaped or angular 10 material with the edges bent over as indicated by numeral 34. It is customary to have the hood suspended from the stove but I have found that this necessitates careful leveling of the stove in order to get the 15 lower edge of the hood evenly spaced from the floor. By using supports and resting them on the floor surface the hood will always be properly spaced from the floor surface.

20 From the above it will appear that I have invented a brooder stove that can be cheaply made and which is substantial in construction and automatic in its operation.

Having now described my invention or 25 discovery, what I claim as new is:

1. A stove comprising in combination, a base portion, a two-part section supported 30 on the base portion, said section being upwardly divergent, a grate located at the juncture of the base and the divergent sections, an air passage extending within said divergent section from a point directly above the grate to the top thereof, a damper 35 hinged to the upper edge of the magazine and adapted to close the upper end of the air passage, a cover on said divergent section, said cover having a feed opening centrally thereof and a flue opening to one side thereof.

40 2. A stove comprising in combination, a base portion, a two-part section supported on the base portion, said section being upwardly divergent, a grate located at the juncture of the base and the divergent sections, an air passage extending within said divergent section from a point directly 45 above the grate to the top thereof, a damper hinged to the upper edge of the magazine and adapted to close the upper end of the 50 air passage, said air passage having a passage into the combustion chamber at some distance above the grate, a cover secured to the top of said divergent portion and having a central feed opening therein 55 and a gas flue eccentrically arranged thereon, said flue opening being arranged diametrically across from the air passage.

3. A stove comprising in combination, a base portion, a two-part section supported 60 on the base portion, said portion being upwardly divergent, a grate located at the juncture of the base and the divergent sec-

tions, an air passage extending within said divergent section from a point directly above the grate to the top thereof, a damper 65 hinged to the upper edge of the portion and adapted to close the upper end of the air passage, said air passage having a passage into the combustion chamber at some distance above the grate, a cover secured to the top of said divergent section and having a central feed opening therein and a gas flue 70 eccentrically arranged thereon, said flue opening being arranged diametrically across from the air passage, and lugs on the outer 75 surface of said portion for supporting a hood.

4. A stove comprising in combination, a base portion, a two-part section supported on the base portion, said section being upwardly divergent, a grate located at the juncture of the base and the divergent section, an air passage extending within said divergent section from a point directly above the grate to the top thereof, a damper 80 hinged to the upper edge of the section and adapted to close the upper end of the air passage, said air passage having a passage into the combustion chamber at some distance above the grate, a cover secured to the top of said divergent section and having a central feed opening therein, and a gas flue 85 eccentrically arranged thereon, said flue opening being arranged diametrically across from the air passage, and thermostatic 90 means for controlling said damper.

5. A stove comprising in combination, a base portion, a two-part section supported on the base portion, said section being upwardly divergent, a grate located at the 100 juncture of the base and the divergent sections, an air passage extending within said divergent section from a point directly above the grate to the top thereof, a damper hinged to the upper edge of the section and 105 adapted to close the upper end of the air passage, said air passage having a passage into the combustion chamber at some distance above the grate, a cover secured to the top of said divergent section and having a 110 central feed opening therein and a gas flue eccentrically arranged thereon, said flue opening being arranged diametrically across from the air passage, a hood, a thermostatic means supported on the inside of said 115 hood near the bottom thereof, means connecting said thermostatic means to the damper whereby the latter is controlled in accordance with the temperature, and supports secured to the lower edge of the hood, 120 for supporting the same from the floor.

In testimony whereof I affix my signature.

WILLIAM H. WALTER.
